His ATTORNEY.

UNITED STATES PATENT OFFICE.

JULIUS J. KARGES, OF MAYWOOD, MISSOURI.

DISPLAY DEVICE.

1,107,075.

Specification of Letters Patent. Patented Aug. 11, 1914.

Application filed January 26, 1914. Serial No. 814,292.

To all whom it may concern:

Be it known that I, JULIUS J. KARGES, a citizen of the United States, residing at Maywood, in the county of Jackson and State of Missouri, have invented certain new and useful Improvements in Display Devices, of which the following is a specification.

My invention relates to improvements in display devices.

One object of my invention is to provide a display device, such as a stand, of novel construction which may be extended to a considerable height or contracted to an exceedingly compact form, which may be quickly and easily extended or contracted and which will reliably support a considerable weight in any position to which it may be adjusted.

A further object of my invention is to provide an extensible device, such as a display stand, with a fitting longitudinally adjustable thereon and having one or more lateral arms, whereby articles carried by said arms may be disposed at any desired height within the limits of the device.

Another object of my invention is to provide a display stand which is adjustable as to length and which is adapted to carry a longitudinally adjustable fitting provided with one or more lateral extensible arms adapted to support articles, whereby the stand is adapted for supporting and displaying articles of various lengths and widths.

Other novel features of my invention are hereinafter fully described and claimed.

In the accompanying drawings, which illustrate the preferred embodiment of my invention as applied to a display stand, Figure 1 is a perspective view of the stand in its extended condition. Fig. 2 is a central vertical sectional view of the same, enlarged, and a portion of the top and part of one of the lateral arms removed. Fig. 3 is a cross section enlarged on the line 3-3 of Fig. 2. Fig. 4 is a cross section enlarged on the line 4-4 of Fig. 2. Fig. 5 is a cross section enlarged on the line 5-5 of Figs. 2 and 6. Fig. 6 is an enlarged vertical fragmental view partly in vertical section and partly in elevation of a portion of the standard. Fig. 7 is an enlarged cross section on the line 7-7 of Fig. 2.

Similar reference characters designate similar parts in the different views.

1 designates a hollow base provided at its top with an internally screw-threaded tubular extension 2, in which is fitted an externally screw-threaded collar 3, in which is secured a vertical tubular member 4 having slidably mounted therein a tubular member 5, in which is also slidably mounted a tubular member 6, on which is longitudinally slidably mounted a tubular fitting 7 having one or more laterally extensible arms comprising each a horizontal tube 8, in which is secured a tube 9, in which a horizontal rod 10 is slidably mounted.

For holding the tube 5 releasably in the tube 4 in such position to which it may be adjusted, said tube 5 is provided with a peripheral annular groove 11 having a peripheral hole 12 in which extends one end of a transversely divided resilient ring 13, which is held compressed by the outer tube 4. The ring 13, by reason of its bearing against the inner periphery of the tube 4, and by reason of its being located in the groove 11, releasably holds the tubular member 5 by frictional means from being moved from the position to which the tubular member 5 may be adjusted.

To prevent the tubular member 5 from being withdrawn from the member 4, the latter is provided adjacent to its upper end, with an inner annular groove 14, Fig. 2, the upper side of the groove being abrupt and its lower side inclined. Said groove 14 is adapted to receive a transversely divided resilient ring 15 which is located in a peripheral groove 16 provided in the outer side of the tube 5 above the groove 11. The tubular member 4 holds the spring ring 15 normally compressed, excepting at such time as the member 5 is drawn to a position in which the ring 15 will be in register with the groove 14, at which time said ring will expand into said groove 14, and will be prevented by the abrupt upper edge of said groove from being withdrawn from the tubular member 4. As the lower side of the groove 14 is inclined, downward pressure applied with sufficient force against the tubular member 5 will cause said tubular member to force the compressible ring 15 downwardly out of the groove 14 to such position as it may be desired to move the same. When the ring 15 is out of the groove 14, it will assist the ring 13 in holding the tubular member 5 in the position to which it may be adjusted. In some instances and

for some purposes the ring 13 may be eliminated.

The tube 6 is provided, as is the tube 5, with two annular peripheral grooves 11 and 16 respectively containing transversely divided resilient rings 13 and 15. The tube 5 is also provided adjacent to its upper end with an annular inner groove 14 similar in shape and adapted for the same purpose as the groove 14 in the tube 4. Each of the grooves 16 is provided with a transverse hole 17, Fig. 6, which is adapted to receive one of the inturned ends of the ring 15. The inturned ends of the rings 13 and 15 serve to retain said rings from circumferential movement in said grooves, and being held compressed by the tube 4, the rings resist turning of the member 5 in the member 4. In the upper end of the tube 6 is secured 20 a tube 18, which is provided with a transverse notch in which is mounted a bow spring 19 having its convex side resting upon the wall of the tube 18, the spring being held compressed by the tube 6. The notch 20 in which the spring 19 is located is cut through the wall of the tube 18, so that a rod 21 fitted in the tube 18 will have the bow spring 19 bearing against its periphery. The rod 21 will thus be releasably held in any position to which it may be adjusted, or it may be entirely removed from the tube 18, in which event the bow spring will still be held in operative position.

If desired, the rod 21 may have its upper end rigidly secured in the lower end of a tube 22, which is rigidly secured in a tube 23, and which is provided with a transverse notch 24, similar to the notch 20 and containing a bow spring 25 similar to the bow spring 19 and adapted to bear against a removable rod 26 having secured to its upper end a rectangular frame 27, Fig. 1, adapted to support an article, such as a hat, not shown. The tube 23 normally holds the bow spring 25 compressed against the wall of the tube 22. Each of the tubes 8 has secured in it a tube 9 provided with a transverse peripheral notch 28, which extends through the wall of the tube 9 and which contains a bow spring 29, the convex side of which is supported by the tube 9 and which is adapted to bear against and have frictional contact with the adjacent rod 10. This rod may be inwardly or outwardly adjusted, or it may be wholly removed.

For releasably holding the fitting 7 in the position to which it may be adjusted on the tubular member 6, said fitting has mounted in it and secured thereto a tube 30 opposite sides of which, as shown in Fig. 3, are provided with transverse notches 31, which are cut through the walls of the tube 30 and have mounted respectively in them two flat flexible plates 32 against which are adapted 65 to bear the convex sides, respectively, of

two bow springs 33 which are held compressed by the fitting 7. The plates 32 are preferably of brass and are bowed similarly to the springs 33 and are adapted to bear against the periphery of the tubular member 6. By having the plates 32 of brass or some relatively soft metal or material, the plates will not scratch or mar the outer surface of the tube 6. The springs 33 may be of hard steel so as to effect the necessary pressure on the plates 32 to reliably hold the tubular member 6 in the position to which it may be adjusted.

In the operation of my invention, the rods 26 and 21 and the tubes 5 and 6 may be moved longitudinally to the positions desired, as can the lateral rods 10. The fitting 7 may be vertically adjusted on the tube 6 to the position desired. By making such adjustments, the device is adapted for supporting cloth goods of different lengths and widths in positions for display, or the device may be employed for the purpose of displaying various other articles.

I do not limit my invention to the structure shown and described, as modifications, within the scope of the appended claims, may be made without departing from the spirit of my invention.

Having thus described my invention, what I claim and desire to secure by Letters Patent, is:—

1. In a display device, two members, one of which is tubular and in which the other is longitudinally slidable, the inner member having an annular groove, and a transversely divided resilient ring mounted in said groove and held compressed by the tubular member.

2. In a display device, two members, one a tubular member in which the other is longitudinally slidable, the tubular member having a stop in its inner periphery, and a transversely divided resilient ring encircling the inner member and held from longitudinal movement thereon and adapted to have its movement in the outer member limited by said stop, the outer member holding said ring normally compressed.

3. In a display device, two members, one a tubular member in which the other is longitudinally slidable, the tubular member having an annular groove on its inner periphery, said groove being abrupt at one side and inclined at the other side, and a transversely divided resilient ring encircling the inner member and held from longitudinal movement thereon and held compressed by the tubular member and being adapted, when moved into register with said annular groove to expand therein so as to lock the inner member against longitudinal movement in one direction.

4. In a display device, two members, one tubular and the other longitudinally slid-

able therein, the tubular member having an inner annular groove inclined at one side and abrupt at the other, the inner member having an annular peripheral groove, and a transversely divided resilient ring mounted in the groove in the inner member and held compressed by the outer member, and adapted, when moved into register with the groove in the outer member, to enter said groove so as to lock the inner member against longitudinal movement in one direction.

5. In a display device, two members, one of which is tubular and in which the other is longitudinally slidible, the inner member having a peripheral hole, and a transversely divided resilient ring encircling the inner member and having a portion extending into said hole, so as to hold it from dis-

placement on said inner member, the ring 20 being held compressed by said outer member.

6. In a display device, two members, one of which is tubular and in which the other is longitudinally slidible, the inner member 25 having a peripheral annular groove, and a transverse hole in said groove, and a transversely divided resilient ring located in said groove and having a portion extending into said hole and held compressed by said tubular member.

In testimony whereof I have signed my name to this specification in presence of two subscribing witnesses.

JULIUS J. KARGES.
